4 Claims. (Cl. 242—7)

This invention relates to lead-dressing tools, and more particularly to devices for applying leads to terminals and for moving portions of the leads away from the portions thereof attached to the terminals and to which solder is to be applied.

An object of the invention is to provide new and improved lead-dressing tools.

Another object of the invention is to provide a device for winding a bared end of an insulated lead onto a terminal and for moving the insulated portion of the lead away from the portion wound onto the terminal to protect the insulated portion from damage when the lead is soldered to the terminal.

A further object of the invention is to provide a sleeve having a notch therein which may be slid over a terminal having a bared end portion of an insulated lead wire wound onto the free end of the terminal to move the insulated portion along the terminal and to partially form the insulated portion around the terminal so that it will stay in a position removed from the bared end of the lead wire.

An apparatus illustrating certain features of the invention may include a sleeve having a notch therein for receiving an insulated portion of a lead, and which may be telescoped over a terminal to move the insulated portion of the lead to a position extending along the terminal and directed away from the bared end thereof wound around the terminal and for turning the lead as it is so moved to partially wrap the lead around the terminal. The sleeve may be mounted on a gun for winding the lead onto the terminal and means may be provided for actuating the sleeve to dress the lead after it has been applied to the terminal.

Other objects and advantages of the invention will become apparent by reference to the following detailed description thereof and the attached drawings illustrating a preferred embodiment of the invention in which,

Fig. 1 is an elevational partial sectional view of a device forming one embodiment of the invention and showing the device applying a lead to a terminal;

Fig. 2 is an enlarged vertical section taken along line 2—2 of Fig. 1;

Fig. 3 is a fragmentary side elevational view of an article with which the tool shown in Fig. 1 is used; and

Fig. 4 is a fragmentary top plan view of the article shown in Fig. 3.

Referring now in detail to the drawings, there is shown in Fig. 1 a lead applying and dressing device comprising a wrapping tool 10 for winding a bared end portion 11 of an insulated lead or conductor 12 onto a terminal 14 adjacent the free end thereof, and a lead-dressing sleeve 20 for moving the insulated portion 15 of the lead 12 along the terminal and partially around the terminal to hold the insulated portion of the lead 12 away from the end of the terminal 14 so that when leads 12 have been applied to a plurality of closely positioned terminals 14 on an article 16 as shown in Fig. 3, the insulated portions of the leads are spaced and directed away from the

tips of the terminals 14 and are not damaged by heat when solder is applied to the wound portions 11 of the lead 12.

The wrapping tool 10 may be similar to those disclosed and claimed in R. E. Bennett Patent No. 2,635,819, issued April 21, 1953, for "Apparatus for Wrapping Strands on Terminals," and L. E. Haagensen Patent No. 2,688,449, issued September 7, 1954, for "Wire Winding Tools," and includes a stationary barrel 21 having a notch 22 therein for receiving and holding a lead 12. Rotatably mounted in the barrel 21 is a spindle 23 having an axial recess 24 for receiving the end of a terminal 14 therein and having a longitudinally extending groove or bore 25 in eccentric relation to the axis of the spindle 15 for receiving the bared end of the lead 12.

The lead-dressing sleeve 20 is slidably mounted on the barrel 21 of the wrapping tool 10 for axial and rotary movements and is adapted to be moved from a normal retracted or inoperative position shown in full lines in 20 Fig. 1 to an advanced or operative position shown in dotted lines. A radially disposed notch 30 in the leading edge of the sleeve 20 is adapted to receive the lead 12 therein and impart turning movement thereto to wind the lead partially around the terminal as it is being moved 25 axially thereof. This rotary movement of the sleeve is effected by a pin 34 on the barrel 21 extending into a slot 36 in the sleeve 20, the slot having a straight portion 37 permitting the sleeve 20 to be moved into engagement with the lead and having a curved portion 38 30 for imparting rotary movement to the sleeve and the lead 12 after the sleeve engages the lead.

The sleeve 20 is moved longitudinally by means of a push rod 40 which is guided for longitudinal movement in a pair of mounting brackets 42 on the housing of the 35 wrapping tool 10 and which has a yoke 44 secured to its forward end. The yoke 44 has a pair of pins 46 extending into an annular groove 48 in the sleeve for effecting a connection thereto. At its other end the rod 40 is connected to one end of a lever 50 pivotally mounted intermediate its ends at 51 on the wrapping tool 10 and having a handle 52 by means of which the operator may actuate the dressing sleeve 20 to its operative position. A spring 54 returns the push rod 40 and the dressing sleeve 20 to the normal inoperative position.

In the operation of the device, the bared end 11 of the lead 12 is inserted in the groove 25 of the spindle 23 of the wrapping tool, the lead 12 positioned in the notch 22 of the barrel 21, the wrapping tool applied to the end of the terminal 14 and actuated to wind the end 50 11 around the terminal, and on completion of the lead-winding operation the operator actuates the lever 52 to move the dressing sleeve 20 longitudinally along the barrel into engagement with the lead 12 and cause the lead to seat in the groove 30 therein, and then to wrap a portion of the lead 12 partially around the terminal 14 as the lead 12 is moved away from the end 11 into close proximity or engagement with the mounting plate or article 16 on which the terminals are mounted.

It will be seen from Figs. 3 and 4 that the leads applied in this manner extend along the terminal and away from the wound end of the leads and are partially bent around the terminal adjacent the article 16 and are maintained thereby in spaced relation to the wound ends of the leads so that when the wound portions 11 of the leads are soldered to the terminals 14, the insulated portions of the leads will not be damaged thereby.

It is to be understood that the above-described arrangement is simply illustrative of the application of this invention. Numerous other arrangements may be readily devised by those skilled in the art which will embody 70 the principles of the invention and fall within the spirit and scope thereof.

What is claimed is:

1. A lead-applying device, which comprises a wrapping tool for winding an end portion of a lead wire around an end of a terminal and having a stationary external barrel, a dressing sleeve mounted on the barrel of the tool for movement between a retracted position wholly on the barrel of the tool and an operative position extending a substantial distance beyond the barrel, resilient means on the tool for moving the sleeve to and yieldably holding it in its retracted position, and manually operable means on said tool for moving the sleeve from its retracted position to its operative position.

2. A lead-applying device comprising a wrapping tool for winding an end portion of a lead wire around an end of a terminal and having a stationary external barrel, a dressing sleeve mounted on the barrel for axial and rotary movements between a retracted position wholly on the barrel of the tool and an operative position extending a substantial distance beyond the barrel, means on said tool for moving the sleeve axially from its retracted position to its operative position, and means for turning the sleeve on the barrel in response to movement of the sleeve to its operative position.

3. A device for applying lead wires to terminals, which comprises a wrapping tool having a stationary external barrel and means within said barrel for engaging an end of a terminal and winding an end portion of the lead

wire onto the end of the terminal, a sleeve having a wire-receiving notch in an end thereof mounted for axial and rotary movement on the barrel, said barrel and said sleeve being provided with a pin and slot connection for imparting rotary movement to the sleeve as the sleeve is moved axially along the barrel, and manually operable means for moving the sleeve along the barrel.

4. A device for applying insulated conductors to terminals, which comprises a wrapping tool for winding a bared end portion of a conductor onto the end of the terminal and having a stationary barrel, a sleeve mounted for axial and rotary movements on the barrel and having a notch in an end thereof for receiving the insulated conductor and having a peripheral groove; said barrel and said sleeve being provided with a pin and slot connection for imparting rotary movement to the sleeve as the sleeve is moved axially along the barrel, a push rod mounted on the wrapping tool for movement parallel to the barrel, a yoke on said rod having pins extending into the peripheral groove in the sleeve, and manually operable means for moving the push rod.
